(57) **CLAIM**

The ornamental design for a height safety trolley rigid rail as shown and described.

DESCRIPTION

FIG. 1 is a front perspective view of a height safety trolley rigid rail, showing our new design;

FIG. 2 is a top plan view thereof;

FIG. 3 is a left side elevation view thereof;

FIG. 4 is a right side elevation view thereof;

FIG. 5 is a bottom plan view thereof;

FIG. 6 is a front elevation view thereof; and,

FIG. 7 is a rear elevation view thereof.

1 Claim, 7 Drawing Sheets
